FLASHLIGHT

John R. Aufiero, Brooklyn, N. Y.

Application April 13, 1943, Serial No. 482,831

3 Claims. (Cl. 240—10.5)

This invention relates to a structurally and functionally improved flashlight and in its more specific aspects aims to provide a unit of this character which may be readily carried and which will furnish adequate illumination for long periods of time and under extremes of temperature and general climatic conditions.

It is well appreciated that considerable difficulty has been experienced with respect to flashlights and where they are operated under extremes of temperature and humidity. Under such circumstances, the dry cells—upon which the operation is dependent—have rapidly become inoperative. Also, during the period of their life, they have frequently furnished improper voltages. Additionally, they have failed completely, even prior to initial use.

With the foregoing in mind, the present invention aims to provide a flashlight which may readily be carried and which will be entirely independent of dry battery cells (at least insofar as direct operation of the light bulb is concerned).

Thus, a dependable unit is provided and which may be relied upon to furnish adequate illumination whenever called upon and which unit will be so constructed that it will not be detrimentally affected by either extremes of temperature or humidity.

A further object of the invention is that of furnishing a device of this type and which may be readily operated to either energize or de-energize the associated light bulb or source of illumination.

Another object is that of furnishing a flashlight embracing a structure which may be readily provided by means of a series of standard units supplemented only—if desired—by certain features which are capable of ready and economical manufacture.

With these and other objects in mind, reference is had to the attached sheet of drawings illustrating a practical embodiment of the invention, and in which:

Fig. 1 is a sectional plan view taken through a flashlight casing and showing the apparatus disposed within the same;

Fig. 2 is a sectional side view taken along the lines 2—2 and in the direction of the arrows as indicated in Fig. 1;

Fig. 3 is a fragmentary transverse view taken along the lines 3—3 and in the direction of the arrows as indicated in Fig. 1; and

Fig. 4 is a diagrammatic illustration of one form of circuit which may be included within the foregoing apparatus.

Referring primarily to Figs. 1 and 2, it will be seen that the reference numeral 5 indicates a casing which may be rectangular and provided with an integral cross-bar extension 6. A cover 7 is formed with a cut-out such that when the cover is applied to the casing, the surfaces of the cross-bar 6 will be contiguous with the adjacent surfaces of the cover. A handle 8 may be mounted by the cover 7 and securing means indicated at 9 may normally lock the cover with respect to the casing so that the entire unit may be transported as a single assembly and by means of the handle 8. When removed from the casing, the cover may be discarded and the casing may still readily be carried by employing the cross-bar 6 as a handle. Normally, however, for protection of the parts the cover should remain applied to the casing.

Secured to the forward end of the casing in 20 any desired manner is extension 10. The latter may mount a reflector 11 which in turn supports a bulb 12 of any proper voltage and type. The head of the latter, of course, extends in advance of the reflector and in turn in advance of that 25 element a lens or transparent cover 13 may be mounted. These several elements may be capable of disassembly and attachment to each other in any desired and conventional manner.

Disposed within the casing 5 is an internal 30 combustion motor 14. The latter may be of more or less conventional type and of the design commonly employed to drive miniature airplanes, motor boats, etc. A driving shaft 15 extends from this motor and is coupled to a generator 16. The 35 latter is secured against movement with respect to the casing and in proper alignment with the motor; a terminal 17 extending from the generator and, if desired and as shown in Figs. 1 and 2, being in direct engagement with the terminal of the bulb 12 by means of a connecting piece 18.

Now with a view to providing a mechanism which will enable an operator to start motor 14 and consequently drive the generator 16 to energize the bulb 12, attention is directed particularly to Fig. 3. In that view, it will be noted that the reference numeral 19 indicates a cap or head portion secured to a plunger 20 slidably mounted by the casing 5. This plunger is extended in the form of a rack 21, the teeth of which mesh with the teeth of the pinion 23. A spring 22 may serve to normally retract the rack and plunger. The interior of the pinion is formed to provide a series of wedge-recesses which receive rollers or balls 24. Obviously, as the

plunger 20 is projected against the action of the spring 22, the pinion 23 will be rotated to cause corresponding rotation of shaft 15. When the latter once begins to rotate, the clutching elements 24 will disengage so that the shaft may readily spin with respect to the pinion. Consequently an entirely satisfactory starting mechanism for the internal combustion engine is furnished.

Thus, in the usual manner, the several accessories of the motor 14 may be potentialized for starting and for this purpose the cover 7 may be removed, if desired. Such potentialization may include priming of the engine, temporary adjusting of the carburetor to assure an initially rich mixture, etc. Thereafter, by projecting the plunger 20, the pinion 23 will be rotated to spin the shaft 15 to start the engine. When the shaft 15 once begins to rotate, the generator 16 will be driven to produce current. This generator may either be of the direct current or alternating current type. In any event, current will flow from the generator to energize the filament of bulb 12 and thus the illumination desired will be furnished by the flashlight. When it is desired to interrupt the operation of the latter, this may readily be accomplished by simply stopping the operation of the engine 14 in one of the several well-known manners.

Having in mind that a unit of this type is to be independent of flashlight cells, the shaft 15 may mount a magneto diagrammatically indicated by the reference numeral 25. The leads, condensers, etc., commonly employed in this connection have not been illustrated in that they are well known to those skilled in the art. Suffice it to say that this magneto will serve to energize the spark plug of the engine 14 so that simultaneously with a rotation of the shaft 15 current adequate for ignition will be furnished. The magneto unit need not necessarily be furnished but, in certain respects, it may be desirable to employ at least a flywheel at this point in order to stabilize the operation of the shaft 15.

In certain instances, it might be desired to energize and de-energize the filament of the bulb 12 without stopping and starting the engine 14. Under these circumstances, an actuator 32 may be employed which, as shown in Fig. 2, may be mounted on the cross-bar 8. Referring to Fig. 4, it will be noted that a circuit has been diagrammatically indicated and which includes a lead 28 extending from the bulb 12 and terminating in a contact 27. A second contact 28 may be disposed immediately adjacent contact 27, and a lead 29 may extend from this contact to, for example, a resistance 30 which, in common with the bulb 12, is grounded. A contact 31 sequentially traverses contacts 28 and 27 and is secured to the actuator 32. This contact is electrically coupled to the generator 16.

In operation, the actuator 32 may be moved from the position shown in Fig. 4 to the left. Thus, contact 31 will engage contact 28 and any current which has been built up by the generator will be dissipated through lead 29 and resistance 30 to the ground. Only after contact 31 has traversed contact 28 does it engage contact 27 to energize the bulb. Due to the aforementioned dissipation of current, there will be no danger of a sudden and high-voltage flowing through the bulb with the result that the filament of the bulb 12 might be burned out.

Also, due to variations in R. P. M. of the engine 14, large variations in voltage from the generator 16 might result. In order to avoid difficulties in this connection and as again indicated in Fig. 4 a voltage regulator 33 in the form of a coil may be interposed in the circuit. Thus again, any danger of the bulb filament's being burned out by too high speed operation of the engine 14 will be avoided.

As will be understood, the illustration of Fig. 4 is only diagrammatic. The elements included within this showing might be modified in many different manners. If desired, a dual wire system might be employed in lieu of the single lead and ground system which has been shown. Also, it is not necessary in many instances that a magneto be utilized to provide the initial spark.

In this connection, attention is again invited to Fig. 1 particularly, in which the numerals 34 indicate wires which may be included within the casing and which may extend from the generator through to the spark coil 35. A condenser 36 may be included in the circuit and a lead may properly extend through to the circuit breaker 37 in order to assure that a proper spark may be generated by the plug of the engine and in time sequence with the operation of the latter.

As also shown especially in Fig. 2, the exhaust pipe of the engine may extend beyond the casing so that products of combustion will not have to escape through the joint of the latter. Obviously, any desired muffling structure might be associated with this exhaust pipe, although this has not been shown. Also, in the leads as illustrated especially in Fig. 1, it is apparent that any desired element might be interposed within the circuit to assure a sufficiently "hot" spark even under initial manual turning of the generator at the time the engine is to be started.

Thus, among others, the several objects of the invention as specifically aforesaid are achieved. Obviously, numerous changes in construction and rearrangements of the parts might be resorted to without departing from the spirit of the invention as defined by the claims.

I claim:

1. A flashlight including in combination a casing adapted to be carried in the hand of the user, an internal combustion engine disposed within said casing, a current generator also disposed within said casing and connected to said engine to be operated thereby, a bulb disposed adjacent one end of said casing, engine-starting means connected to initiate operation of said engine, switch means for connecting said generator and bulb and including relatively movable and engageable parts coupled to said bulb and generator, and charge-dissipating means engageable by one of said parts prior to its engagement with the second part.

2. A flashlight including in combination a casing adapted to be carried in the hand of the user, an internal combustion engine disposed within said casing, a current generator also disposed within said casing and connected to said engine to be operated thereby, a bulb disposed adjacent one end of said casing, engine-starting means connected to initiate operation of said engine, said starting means extending beyond the exterior of said casing, and switch means connected to said generator and bulb, charge-dissipating means, a contact connected with said bulb, and a manually shiftable element adapted to successively traverse said charge-dissipating

means and contact, said element being connected to said generator.

3. A flashlight including in combination a casing adapted to be carried in the hand of the user, an internal combustion engine disposed within said casing, a current generator also disposed within said casing and connected to said engine to be operated thereby, a bulb disposed adjacent one end of said casing, engine-start-

ing means connected to initiate operation of said engine, said starting means extending beyond the exterior of said casing, covers forming portions of said casing and removable therefrom, a cross-bar fixed with respect to said casing, and a switch element carried by said cross-bar and connected to said generator and bulb to establish a path of current flow between the same.

JOHN R. AUFIERO.
